CONTROL DEVICE FOR A MACHINE

Charles R. Blockside, Albany, N. Y., assignor to
 A. P. W. Paper Company, Albany, N. Y., a Corporation of New York

Application December 26, 1931
 Serial No. 583,321

9 Claims. (Cl. 192—131)

My invention more particularly relates to a control device with associated means for normally preventing the actuation of the control, and which requires the use of both hands by 5 the operator to actuate the same.

In the operation of machines, and particularly those where the operator is paid by the piece, he is prone, in order to gain time, to use one hand to actuate the control mechanism for 10 starting the machine and, at the same time, to use the other hand in feeding material to the machine. For example, in the paper making industry, operators are accustomed to actuate the control mechanism with one hand, and at the 15 same time place the paper in position to be fed into the machine with the other hand, with the result that the fingers of the operator are likely to be caught between the rolls which results not only in injury to the operator but in crippling 20 the operation of the machine.

It has been proposed to overcome the foregoing difficulty by the use of two manually operable handles intended to require the use of both hands in order to start the machine. With 25 such devices, however, it has been found that the operator will actuate the one handle and tie it in position, thereby enabling him to operate the control with one hand and encounter the very dangers above pointed out.

30 My invention overcomes the foregoing difficulties by the provision of a control device comprising two manually operable members which must be grasped by the respective hands of the operator in order to start the operation of the machine. My invention will best be understood 35 by reference to the accompanying drawing in which I have illustrated a preferred embodiment and in which—

Fig. 1 is a front view of a control device embodying my invention;

Fig. 2 is a sectional plan view of the control device taken along the line 2—2 of Fig. 3;

Fig. 3 is a sectional view similar to Fig. 2 taken at right angles thereto;

45 Fig. 4 is a sectional view similar to Fig. 3 illustrating the parts in the position where the locking means which normally prevents movement of the control device have been withdrawn; and

50 Fig. 5 is a view similar to Figs. 3 and 4 illustrating the parts in a different position from those shown in Fig. 4.

Like reference characters indicate like parts throughout the drawing.

55 Referring now to the drawing, 10 indicates

generally a control device embodying my invention mounted, in the embodiment illustrated, in openings 11 in standards 12 which are in turn secured to a frame 13 which may or may not constitute a part of the associated machine. 60

In the embodiment of my invention illustrated, the device 10 is pivotally connected as at 14 to a control element 15 which is in turn pivotally mounted, as at 16, on the frame 13. The lower end of the element 15 engages one element 17 of a clutch mechanism which, in order to start the operation of the machine, must be moved to the left, as viewed in Fig. 1, and engage the complementary clutch element 18. While I have illustrated my invention in connection with a 70 clutch for starting the operation of the machine, it will, of course, be obvious that it is equally applicable to the operation of an electric switch for starting the operation of a machine, for actuating a valve for starting an engine, or for 75 any other suitable control.

Normally, the movement of the element 10 to the right, as viewed in Fig. 1, is prevented by a latch or lock 19 which projects downwardly therefrom and engages a lug 20 secured on the 80 standard 12. In order to release this latch or lock and enable the operator to move the member 10 to the right, as viewed in Fig. 1, it is necessary for the operator to grasp two manually operable members with his respective hands 85 in a manner that will now be described.

Referring, now more particularly to Figs. 2 to 5, the control device indicated generally at 10, in the embodiment illustrated, comprises an inner hollow telescoping member 21 and an outer hollow telescoping member 22 which are 90 relatively movable in order to release the latch 19 and which are jointly movable in a direction to actuate the control element for starting the operation of the machine; that is to say, after the latch or lock has been withdrawn in response to the relative movement of the two members, the two members are then jointly moved to the right, as viewed in Fig. 1, in order to actuate the control element 15. Two spaced members 23 and a member indicated generally at 24, are secured to the inner telescoping member 21 and the outer telescoping member 22, respectively, as by pins 25 and 26, the latter passing through oppositely disposed openings 27 in the wall of the inner telescoping member 21. The member 24 is preferably somewhat elongated as illustrated and comprises a head 28 connected to a head 29 by a contracted portion 30. 100

105

110

The end of the member 29 is preferably forked as at 31 to receive one portion 32 of a locking member 33, which is preferably in the form of a plate, the portion 32 being provided with a recess 34 in which is received a pin 35 secured to the branches of the forked end 31. The locking member 33 is pivotally mounted as at 36 on a head 37 which is received in the inner telescoping member 21 and which may, if desired, have a loose fit therein by the provision of opposite slots 38 in the inner telescoping member in which a pin 39 passing through the head 37 is received.

A compression spring 40 is interposed between the heads 23 and 28, and normally moves the head 28 away from the member 23 until the pin 26 occupies a position at the right hand end of the slots 27, as viewed in Fig. 2. The member 24 is thereby moved to its extreme position to the right and the pin 35 rotates the locking member 33 about the pivot 36 and thereby causes the locking member 33 to extend through an opening 41 in the tubular telescoping member 21 and engage the lug 20. If an attempt is made to move the two manually operable members comprising the control device 10 to the right, as viewed in the drawing, the locking member 33 engages the lug 20. In order to release the locking member 33, it is necessary for the operator to grasp the two telescoping members 21 and 22 with the respective hands, and move his two hands which are grasping the respective elements towards each other; in other words, the inner telescoping member 21 must be moved to the left with respect to the outer telescoping member 22, as viewed in Fig. 2. The spring 40 is thereby compressed, the pin 35 rocks the locking member 33 anticlockwise about the pivot 36 and withdraws the locking member into the inner telescoping member 21 to the position indicated in Fig. 4. Then the operator, while still retaining his grasp on the separate manually operable members, may move them jointly to the right, as viewed in Fig. 1, so that the control element 15 is actuated in a direction to close the clutch and start the operation of the machine.

The lower edge of the locking member 33 is preferably beveled at 42 so that in the event the locking member is moved to a position beyond the standard 12, the operator can withdraw the control device 10 with one hand, the latch then riding up into the opening 11 in the standard.

The means associated with the two telescoping members 21 and 22 for releasing the latch are housed within these members and thereby are concealed and inaccessible to the operator, and he is, therefore, compelled to use both hands in actuating the control device.

It will, of course, be understood that the spring 40 will be made sufficiently stiff to preclude the operator taking hold of the extreme end of the outer telescoping member 22 and the inner member with one hand and thereby bringing about the operation with a single hand.

While I have described my invention in its preferred embodiments it is to be understood that the words which I have used are words of description and not of limitation and that changes within the scope of the appended claims may be made without departing from the true scope and spirit of my invention in its broader aspects.

What I claim is:

1. In a device of the character described, a control element for a machine, two manually operable members jointly movable in one direction for actuating said element, means for normally preventing the joint movement of said members in said direction, said members being relatively movable, and associated means normally inaccessible to the operator and responsive to the relative movement of said members for releasing said means. 80

2. In a device of the character described, a control element for a machine, two manually operable members jointly movable in one direction for actuating said element, means for normally preventing the joint movement of said members in said direction, said members being relatively movable, yielding means normally resisting the movement of said members, and means normally inaccessible to the operator and responsive to the relative movement of said members for releasing said means. 90

3. In a device of the character described, an element for controlling the operation of a machine, two manually operable members connected together and jointly and relatively movable, and associated means normally inaccessible to the operator and responsive only to the relative and joint movements of said members for actuating said element. 100

4. In a device of the character described, an element for controlling the operation of a machine, two manually operable relatively movable members connected together, one of said members being operatively connected to said element, means for normally locking said last mentioned member against movement in a direction to actuate said element, and associated means normally inaccessible to the operator and responsive to the relative movement of said members for releasing said locking means. 110

5. In a device for controlling the operation of a machine, two manually operable telescoping members jointly movable in one direction to start the operation of the machine, locking means normally preventing movement of said member in said direction, said members being relatively movable, and associated means housed within said members and responsive to the relative movement thereof for releasing said locking means. 120

6. In a device for controlling the operation of a machine, two manually operable telescoping members jointly movable in one direction to start the operation of the machine, locking means normally preventing the movement of said member in said direction, means for yieldingly resisting the relative movement of said members, and associated means housed within said members and responsive to the relative movement thereof for releasing said locking means. 130

7. In a device of the character described, an element for controlling the operation of a machine, two manually operable telescoping members jointly and relatively movable, means responsive to the joint movement of said members for actuating said element, a latch projecting through one of said members for normally preventing the joint movement of said members and associated means housed within said members and responsive to the relative movement thereof for withdrawing said latch within the associated member. 140

8. In a device of the character described, a 150

control device for a machine, two manually operable hollow telescoping members for actuating said control, two spaced devices located in the respective members, one of said devices being fixedly attached to the associated member, and the other device being attached to the other member with a lost motion, a latch for normally preventing sufficient movement of said members to actuate said control, and means responsive to the relative movement of said devices for releasing said latch.

9. In a device of the character described, a control device for a machine, two manually

operable hollow telescoping members for actuating said control, two spaced devices located in the respective members, one of said devices being fixedly attached to the associated member, and the other device being attached to the other member with a lost motion, yielding means for normally forcing said devices apart, a latch for normally preventing sufficient movement of said members to actuate said control, and means responsive to the relative movement of said devices for releasing said latch.
